PAPER TOWEL DISPENSER OR SIMILAR ARTICLE

Erwin B. Bahnsen, Hinsdale, Ill., assignor, by mesne assignments, to Georgia-Pacific Corporation, Portland, Oreg., a corporation of Georgia

Filed Mar. 29, 1963, Ser. No. 74,221

Term of patent 14 years

(Cl. D52—2)

FIG. I

FIG. II

Fig. 3

Fig. 4

FIG- 7

FIG. 1 is a perspective view of a paper towel dispenser or similar article embodying my new design;

FIG. 2 is a bottom plan view thereof;

FIG. 3 is a top plan view thereof;

FIG. 4 is a front elevational view thereof;

FIG. 5 is a rear elevational view thereof;

FIG. 6 is a side elevational view thereof, the opposite side not shown being substantially the same; and

FIG. 7 is a cross sectional view thereof taken on line 7—7 of FIG. 5.

The broken line representation of a roll of toweling is for purposes of illustration only.

I claim:

The ornamental design for a paper towel dispenser or similar article, substantially as shown and described.
